FIG. 4

FIG. 5

FIG. 6

FIG. 7

FIG. 1 is a perspective view of one embodiment of the upholstered chair of this invention wherein the backrest consists of two cushions;

FIG. 2 is a side elevation of the chair shown in FIG. 1;

FIG. 3 is a front elevation of the chair shown in FIG. 1;

FIG. 4 is a side elevational view of the chair design wherein the backrest consists of three rather than two cushions; and

FIG. 5 is a front elevation of the embodiment shown in FIG. 4.

FIG. 6 is a rear elevation of the chair shown in FIG. 1; and

FIG. 7 is a rear elevation of the chair shown in FIG. 4.

The design is characterized by a vertical arrangement of elongated back rest members disposed in a contiguous relationship and all in combination with the specifically configured onepiece side frame members, substantially as shown.

I claim:

The ornamental design for an upholstered chair, substantially as shown and described.
